[57] **CLAIM**

The ornamental design for a swag lamp, as shown and described.

DESCRIPTION

FIG. 1 is a perspective view of a swag lamp showing our new design;

FIG. 2 is a side elevational view thereof on a reduced scale;

FIG. 3 is a top plan view thereof on a reduced scale; FIG. 4 is a greatly enlarged view of the portion of the canopy indicated by circle 4 FIG. 2, it being understood that the circular apertures are uniformly continuous over the canopy sides;

FIG. 5 is a second side elevational view thereof;

FIG. 6 is a sectional view taken on line 6—6 of FIG. 5.

Fig. 1.
